UNITED STATES PATENT OFFICE.

THOMAS M. BRINTNALL AND WILLIAM E. SWALM, OF LOS ANGELES, CALIFORNIA,
ASSIGNORS OF ONE-THIRD TO WILLIAM C. BRYAN, OF LOS ANGELES, CALIFORNIA.

LOCK.

1,251,177.

Specification of Letters Patent.

Patented Dec. 25, 1917.

Application filed March 10, 1914. Serial No. 823,669.

To all whom it may concern:

Be it known that we, THOMAS M. BRINTNALL and WILLIAM E. SWALM, both citizens of the United States, residing at Los Angeles, in the county of Los Angeles and State of California, have jointly invented new and useful Improvements in Locks, of which the following is a specification.

This invention relates to locks, and more particularly to adjustable tumbler locks in which the set or combination of the several tumblers may be varied so as to require a different key to operate the lock for each set or combination of the tumblers. Such locks are commonly used for safe deposit box doors and to protect valuable contents of other structures to which they are applied, as their use is a highly efficient protection against tampering by unauthorized persons with pass keys, skeleton keys and the like, or with keys which have been discarded after use in connection with a previous combination or arrangement of the tumblers.

The invention has for its object to provide an improved adjustable tumbler lock, with the above objects in view, and which will be relatively superior in point of simplicity and inexpensiveness in construction and organization, taken in connection with positiveness in operation, convenience and facility in use and adjustment, which affords increased security as against tampering, which will not be liable to easily get out of order, and which will be generally superior in efficiency and serviceability.

With the above and other objects in view, the invention consists in the novel and useful provision, formation, construction, combination, association and relative arrangement of parts, members and features, all as hereinafter described, shown in the drawings and finally pointed out in claims.

In the drawings:

Figure 1 is a front elevation of one particular form of adjustable tumbler lock embodying the invention, with the front casing wall or plate partially broken away for clearness of illustration; the parts of the lock, including the bolt, being in locked position and being set for control by the proper keys;

Fig. 2 is a similar view showing the parts of the lock adjusted so as to provide or establish a new combination or arrangement

of the tumblers wherein they will be subject to control of a different pass key;

Fig. 3 is a longitudinal sectional view of the improved lock shown in Fig. 1, taken upon the line x^3-x^3 , Fig. 1, and looking in the direction of the appended arrow;

Fig. 4 is a sectional view taken upon the lines x^4-x^4 , Fig. 1, and looking in the direction of the appended arrow;

Fig. 5 is a view similar to Fig. 1 with the tumblers and face plate removed, permitting a detail showing of the bolt and its adjuncts;

Fig. 6 is a face view of the bolt in detached position;

Fig. 7 is a top edge view of the bolt in detached position;

Fig. 8 is a detail face view, in detached position, of the custodian key tumbler controlled by the custodian key;

Fig. 9 is a similar view of one of the pass key tumblers;

Fig. 10 is a similar view of a master key tumbler a plurality of which coöperate with a plurality of the pass key tumblers in Fig. 9;

Fig. 11 is a similar view of one of a number of spacers which are alternately applied between the several master key tumblers and pass key tumblers;

Fig. 12 is a face view of a custodian key used to operate the custodian key tumbler shown in Fig. 8;

Fig. 13 is the change combination key which is used to operate the tumblers shown in Figs. 8 and 10;

Figs. 14 and 15 are face views of differently formed pass keys, or pass keys constructed with a variation of ward formation, which are to be respectively used in connection with different combinations or arrangements of the pass key tumblers shown in Fig. 9 and the master key tumblers shown in Fig. 10, and which directly operate upon the pass key tumblers, both in producing a different combination of the same and in operating the lock when set; and,

Fig. 16 is a detail sectional view taken upon the line $x^{16}-x^{16}$, Fig. 3.

Corresponding parts in all the figures are designated by the same reference characters.

Referring with particularity to the drawings, A designates the bolt, B designates the master key tumblers and C designates the

pass key tumblers of an improved adjustable tumbler lock constructed to embody the invention. These tumblers with their associated parts are shown as accommodated within 5 in a casing 16, having a detachable front plate 17 permitting the several features to be assembled and removed for repair or replacement. The tumblers B, which are spaced each from the next by one of the 10 spacers D shown in Fig. 11, are, with such spacers, pivotally mounted intermediate of their ends upon an eccentric shaft 18, that is a shaft having eccentrically disposed end bearings 19 which take into suitable bearing 15 openings in the rear wall of the casing 16 and front cover 17. The pass key tumblers are likewise relatively spaced by similar spacers D; and together with the same are journaled on a stud 20, the end of which is 20 fastened to or made integral with the casing 16. Each of the master key tumblers B is formed at one end into a toothed sector 21; and each of the pass key tumblers C is correspondingly provided at one end with a toothed 25 sector 22, such ends being the adjacent ends of the several tumblers B and C, the arrangement being such that normally each of the toothed sectors 21 is in mesh with an opposed toothed sector 22, such arrangement being 30 subject to control of the eccentric shaft 18 which may be manipulated, as hereinafter set forth, to terminate such meshed relation and permit relative pivotal adjustment of the tumblers B and tumblers C. Each of the 35 pass key tumblers C is provided with a tension device consisting of a spring finger 23 one end of which takes into a suitable recess 24' above the respective sector 22, and the other end of which bears against the top 40 wall of the casing 16, such springs all tending to elevate the sector heads and depress the opposite ends of the pass key tumblers which ends, 24, project in a group in position for actuation by such pass key as is 45 applied to the same through a rotating barrel 25 confined within a thimble 26 supported upon the front plate 17 which bridges the interior of the casing 16; said barrel having a longitudinally slotted cylindrical extension 50 25^a which ranges transversely of the casing beneath the series of key-operated ends 24 of the pass key tumblers C; the rearward end of such extension 25^a, being journaled in the rear wall of the casing 16. Immediately 55 within the rear casing wall the extension 25^a is provided with a bolt operating finger 28 which co-operates with the walls of a notch or recess 29 in the shank 30 of the bolt A, to reciprocate the bolt through the extension 25^a under pass key actuation. Suitable stops 31 are provided upon the casing rear wall to limit the rotation of the extension 25^a and the finger 28. The bolt A has the usual operative nose 32 which plays 60 through a suitable opening in the front end

wall of the casing 16, and is free to play longitudinally against the inner face of the rear wall of the casing, having slots 33 and 34 respectively, accommodating the shafts 18 and 20 and thus permitting the bolt to reciprocate. The bolt shank 30 carries immediately behind or inward of the nose 32 a stump 35 which ranges forwardly from the bolt shank and is adapted to enter a series of notches or recesses 36 provided respectively in the ends 37 of the master key tumblers opposite the sector head ends 21; and also to enter a similar recess 38 in the custodian key tumbler E shown in Fig. 8, which latter is held flat against the bolt shank 30, being pivotally mounted upon the eccentric shaft 18, and is held depressed, by a spring finger 39 which engages a nose 40 at the extremity opposite to the recess 38 and likewise bears against the casing top. Normally the slot 38 occupies a depressed position so that the stump 35 cannot enter the same; and the slots 36 are so normally disposed that the stump 35 can enter the same when the bolt is reciprocated by the finger 28 under actuation of the pass key. Means are provided for normally holding the master key tumblers B in the positions shown in Fig. 1, that is with the sector heads 21 in mesh with the sector heads 22 of the pass key tumblers; such means being shown as comprising a leaf spring 41 held at one end by a rivet 42 set into an opening in the rear casing, the other end of the spring bearing upon an angular surface 43 at the rearward end of the eccentric shaft 18.

Each of the master key tumblers B has a recess 44 in its lower portion for insertion of a ward upon the change combination key K; and the custodian key tumbler E has a similar recess 45 in its lower portion to receive a ward upon the change combination key.

In the use and operation of the improved adjustable tumbler lock, referring to the particular embodiment thereof hereinabove described and shown in the drawings, the bolt may be reciprocated by any pass key or common key, such as F and G shown in Figs. 14 and 15, which may be inserted through the slotted barrel 25 and the slotted extension 25^a thereof and beneath the grouped ends 24 of the pass key tumblers C, all as determined by the formation of the wards on the pass key and the grouped arrangement of said tumbler ends which lie above the extension 25^a. The turning of the key will turn the foot 28 and reciprocate the bolt, the stump freely passing in and out of the slots 36 in the master key tumblers B and slot 38 in the custodian key tumbler E. However, to enable this operation of the bolt, in either direction, the custodian key H must first have been inserted through a corresponding slotted barrel 46 mounted in a thimble 47 upon the front casing plate 17

and having a corresponding slotted extension 46^a which is journaled at its far end in the rear casing wall; and provided said custodian key thus inserted has been operated 5 to pivotally swing the custodian key tumbler E so as to bring its recess 38 into position for the stump 35 to be received within the same in common with its reception within the recess 36, as stated above. As long as the custodian key remains inserted, holding the custodian key tumbler in the position stated, the pass key F or G can be employed to reciprocate the bolt in either direction. However, as soon as the custodian key is 10 withdrawn, the custodian key tumbler will swing into position to prevent the bolt from being withdrawn after the stump has left the recess 38 upon the movement of the bolt into locking position. Thus, in order to unlock or withdraw the bolt after it has once been shot it is necessary to apply and manipulate the custodian key H in the manner above specified, and then to use the pass key to withdraw the bolt.

25 In order to change the combination or set of the several master key tumblers and pass key tumblers, the custodian key tumbler E is first manipulated by the custodian key to permit the lock to be unlocked and the bolt 20 to be withdrawn as above stated. The change combination key K, shown in Fig. 13, is then inserted through the slotted barrel 46 when registered with the top notch in thimble 47 so that its several wards enter 25 the several recesses 44 of the master key tumblers B, and the notch 45 in the custodian tumbler E. The slight turning of this key will swing these tumblers away from the pass key tumblers C, by partially turning 30 the eccentric shaft 18, which moves all of the master key tumblers B and custodian key tumbler E in a direction away from the pass key tumblers, unmeshing these two sets of tumblers. A new pass key, such as F or 35 G, is then inserted in the slotted barrel 25 and its extension 25^a beneath the end portions 24 of the pass key tumblers C, and is turned to stand vertical when all of the wards will come into contact respectively 40 with all of said end portions 24; this determines a new set or arrangement of the pass key tumblers C which are now ready 45 for remeshing with the master key tumblers B. This last step is performed by slightly 50 rocking the master key tumblers B and the eccentric shaft 18 through the slight rotation of the change key. The spring 41 will have previously held the master key tumblers in the projected position. In opposition to this spring the said tumblers B are 55 again thrown into normal positions to mesh in altered relation with the pass key tumblers C, in which position the spring 41 now holds them. All of the tumblers B will have 60 been held in proper position to receive the

stump 35 during the change of the combination, because such stump is retained in the recesses or gates of tumblers B during this changing operation, the bolt having been withdrawn by the pass key with this 70 end in view. It results that a new combination of the tumblers has been effected, which combination is only responsive to the custodian key and the new pass key which latter only can so swing the newly arranged 75 pass key tumblers C as to properly swing the master key tumblers B and permit the stump 35 to enter the recesses 36 therein upon the withdrawal of the bolt. The operation of locking and unlocking the bolt, by 80 the use of the new pass key and the custodian key, is the same in all particulars and steps as previously pointed out with relation to the previous set of the tumblers.

It results, as will be manifest, that as 85 many combinations of the tumblers may be provided as keys are provided with different ward formations for producing the same; and that when a new combination is provided only the key which has produced it 90 can operate the lock. No alterations or substitution of the parts or features are required to this end, save and except the provision of a different pass key for each set of the tumblers. 95

The master key tumblers B are shown as of different dimensions vertically so as to render impossible the joint actuation of all these tumblers by any key or implement other than that formed with wards or the 100 like to coöperate with these several tumblers as shown particularly in Fig. 16. Also, we provide an opening 17^a in the front plate 17 of the casing 16 in line with the recesses 36 in the master key tumblers B, and through 105 which a suitable key or implement may be inserted to actuate all of said tumblers to permit the bolt 32 to be withdrawn, the stump 35 entering said recesses 36. This permits the opening of the lock in order to 110 produce a new combination of the tumblers responsive to the formation of a new pass key, in case a given pass key is lost. The wards of the master key would be arranged to actuate both the tumbler E and the master 115 key tumblers B, thereby enabling the bolt to be withdrawn by the use of this key alone.

It is manifest that many variations may be made with respect to the construction and arrangement of the parts and features, and 120 with relation to the foregoing description and drawings, without departing from the spirit of the invention and a fair interpretation of the following claims.

Having thus disclosed our invention, we 125 claim and desire to secure by Letters Patent:

1. An adjustable tumbler lock, comprising: a bolt, a master key tumbler mounted to move in two different paths, a pass key tumbler mounted to move with the master 130

key tumbler during the movement of the latter in one of its paths of movement, a custodian key tumbler through the independent movement of which movement of the bolt 5 is permitted after application of a pass-key to the pass-key tumbler, a stump upon the bolt coöperating with said master key tumbler and said custodian key tumbler to prevent movement of the bolt, and means serving to yieldingly hold the master key tumbler 10 in position for movement in each of its paths.

2. An adjustable tumbler lock, comprising a bolt, a master key tumbler mounted to move in two different paths, a pass key tumbler mounted to move with the master key tumbler during the movement of the latter in one of its paths of movement, a custodian key tumbler through the independent movement of which movement of the bolt 15 is permitted after application of a pass-key to the pass-key tumbler, a stump upon the bolt coöperating with said master key tumbler and said custodian key tumbler to prevent movement of the bolt, and means serving to yieldingly hold the master key tumbler in position for movement in each of its paths; said master key tumbler and said custodian key tumbler being provided each 20 with a recess adapted to receive said stump when the bolt is withdrawn.

3. An adjustable tumbler lock, comprising a bolt, a master key tumbler mounted to move in two different paths, a pass key tumbler mounted to move with the master key tumbler during the movement of the latter in one of its paths of movement, a custodian key tumbler through the independent movement of which movement of the bolt 25 is permitted after application of a pass-key to the pass-key tumbler, a stump upon the bolt coöperating with said master key tumbler and said custodian key tumbler to prevent movement of the bolt, and means serving to yieldingly hold the master key tumbler in position for movement in each of its paths; said master key tumbler and said custodian key tumbler being provided each with a recess adapted to receive said stump when the bolt is withdrawn; and means being provided for normally holding the master key tumbler and the custodian key tumbler in positions to coöperate with the stump to prevent movement of the bolt.

4. An adjustable tumbler lock, comprising a casing provided with an eccentric master key tumbler shaft and a pass key tumbler shaft, a custodian key tumbler pivotally mounted upon the master key tumbler shaft, a plurality of master key tumblers mounted upon the master key tumbler shaft, a plurality of pass key tumblers mounted upon the pass key tumbler shaft, all of said tumblers being pivotally mounted and each 60 of said master key tumblers being arranged

for operative connection with one of said pass key tumblers for joint movement therewith, means normally holding said master key tumbler eccentric shaft in position whereby the said operative connection of 70 said master key tumblers and said pass key tumblers is maintained subject to direct actuation for separation thereof, a bolt mounted to reciprocate within the casing, a stump upon the bolt and coöperating with the master key tumblers and the custodian key tumbler to prevent withdrawal of the bolt, and means normally holding the master key tumblers and custodian key tumbler in positions to so coöperate with the stump.

5. An adjustable tumbler lock, comprising a casing provided with an eccentric master key tumbler shaft and a pass key tumbler shaft, a custodian key tumbler pivotally mounted upon the master key tumbler shaft, a plurality of master key tumblers mounted upon the master key tumbler shaft, a plurality of pass key tumblers mounted upon the pass key tumbler shaft, all of said tumblers being pivotally mounted and each of 80 said master key tumblers being arranged for operative connection with one of said pass key tumblers for joint movement therewith, means normally holding said master key tumbler eccentric shaft in position 85 whereby the said operative connection of said master key tumblers and said pass key tumblers is maintained subject to direct key actuation for separation thereof, a bolt mounted to reciprocate within the casing, a stump upon the bolt and coöperating with the master key tumblers and the custodian key tumbler to prevent withdrawal of the bolt, and means normally holding the master key tumblers and custodian key tumbler in positions to so coöperate with the stump; said custodian key tumbler being adapted to be operated by a suitable key to swing said eccentric master key tumbler shaft so as to operatively disconnect said master key tumblers and said pass key tumblers.

6. An adjustable tumbler lock, comprising a casing provided with an eccentric master key tumbler shaft and a pass key tumbler shaft, a custodian key tumbler pivotally mounted upon the master key tumbler shaft, a plurality of master key tumblers mounted upon the master key tumbler shaft, a plurality of pass key tumblers mounted upon the pass key tumbler shaft, all of said tumblers being pivotally mounted and each of 115 said master key tumblers being arranged for operative connection with one of said pass key tumblers for joint movement therewith, means normally holding said master key tumbler eccentric shaft in position 120 whereby the said operative connection of said master key tumblers and said pass key tumblers is maintained subject to direct key 125 actuation for separation thereof, a bolt mounted to reciprocate within the casing, a stump upon the bolt and coöperating with the master key tumblers and the custodian key tumbler to prevent withdrawal of the bolt, and means normally holding the master key tumblers and custodian key tumbler in positions to so coöperate with the stump; said custodian key tumbler being adapted to be operated by a suitable key to swing said eccentric master key tumbler shaft so as to operatively disconnect said master key tumblers and said pass key tumblers.

- actuation for separation thereof, a bolt mounted to reciprocate within the casing, a stump upon the bolt and coöperating with the master key tumblers and the custodian key tumbler to prevent withdrawal of the bolt, and means normally holding the master key tumblers and custodian key tumbler in positions to so coöperate with the stump; said custodian key tumbler being adapted to 10 be operated by a suitable key to swing said eccentric master key tumbler shaft so as to operatively disconnect said master key tumblers and said pass key tumblers; and means for holding said master key tumblers and 15 said custodian key tumbler in the positions last recited.
7. In an adjustable tumbler lock, a master key tumbler and a pass key tumbler mounted for both joint movement and relative separation and adapted to be jointly actuated by a suitable pass key; a bolt, means upon the bolt coöperating normally with the master key tumbler to prevent movement of the bolt and being freed to permit movement of 20 the bolt upon joint movement of the master key tumbler and the pass key tumbler; and means for relatively moving the master key tumbler and the pass key tumbler by direct key actuation.
- 25 8. In an adjustable tumbler lock, a master key tumbler and a pass key tumbler mounted for both joint movement and relative separation and adapted to be jointly actuated by a suitable pass key; a bolt, means upon the bolt coöperating normally with the master key tumbler to prevent movement of the bolt and being freed to permit movement of the bolt upon joint movement of the master key tumbler and the pass key tumbler; and 30 means for relatively moving the master key tumbler and the pass key tumbler by direct key actuation.
- 35 9. In an adjustable tumbler lock, a master key tumbler and a pass key tumbler mounted for both joint movement and relative separation and adapted to be jointly actuated by a suitable pass key; a bolt, means upon the bolt coöperating normally with the master key tumbler to prevent movement of the bolt and being freed to permit movement of the bolt upon joint movement of the master key tumbler and the pass key tumbler under actuation by the same key.
- 40 10. In a lock of the character disclosed, a master key tumbler and a pass key tumbler mounted for both joint and relative movement and adapted to be jointly operated by a suitable key applied to the master key tumbler; a bolt, means upon the bolt coöperating normally with the master key tumbler to prevent movement of the bolt and being freed to permit movement of the bolt upon joint movement of the master key tumbler and the pass key tumbler under actuation by the same key.
- 45 In testimony whereof, we have signed our names to this specification in the presence of two subscribing witnesses.
